SLIDE TYPE SWITCHES

Irving Gebel, Oak Park, Ill., assignor, by mesne assignments, to Controls Company of America, Schiller Park, Ill., a corporation of Delaware

Application October 4, 1954, Serial No. 460,137

6 Claims. (Cl. 200—67)

One of the objects of my invention is the provision of a switch operated by an actuating lever movable in a straight line direction.

Another object of my invention is the provision of a switch of the foregoing character which is positive in its action when indexed from one position to another.

Still another object of my invention is the provision of a switch structure of the foregoing character in which the actuating lever is accurately located and subject to a very minimum of play in any position of movement.

A further object of my invention is the provision of a switch structure in which the actuating means are so constructed as to be adaptable for use with a variety of contact arrangements for opening or closing a combination of electrical circuits.

A still further object of my invention is the provision of a switch which is compact in arrangement, simple in construction and durable in service.

Other and further objects and advantages of my invention will become apparent from the following description when considered in connection with the accompanying drawings, in which—

Fig. 1 is a top plan view of a switch assembly constructed in accordance with my invention;

Fig. 2 is a front elevational view;

Fig. 3 is an end elevational view thereof;

Fig. 4 is a cross-sectional view taken substantially along line 4—4 of Fig. 2;

Fig. 5 is a cross-sectional view taken substantially along line 5—5 of Fig. 2;

Fig. 6 is a perspective view with certain of the parts in exploded relation and illustrating a modified arrangement of switch contact points;

Fig. 7 is a front elevational view of the structure illustrated in Fig. 6;

Fig. 8 is a rear elevational view of another modified arrangement of the switch contact points; and

Fig. 9 is a cross-sectional view of an enlarged scale substantially along line 9—9 of Fig. 6.

Referring to the drawings, and specifically Figs. 1 through 5, my invention comprises a housing 10 preferably formed of sheet metal and including a rear wall 11 and integral, side and end walls 12 and 13 respectively. The rear wall 11 is provided with integral lugs 11a by which the housing may be suitably attached to a desired point of mounting. The side walls 12 are each provided with an aperture, said apertures being in registration and each receiving a brass eyelet 14 providing a bearing surface for slidably supporting a guide rod 16. The end walls 13 are each provided with a longitudinally extending slot 15 at a lower portion thereof. One of the end walls 13 is provided with a flange 17 adjacent a respective slot, the said flange serving as a bearing surface for one end of an actuating lever 18 presently to be described. The lever 18 extends through the slots 15 in substantially parallel relation to the rear wall 11 and is provided with an extension 19 which may be engaged for manipulating the switch.

2

Suitably secured as with rivets to the lever 18 is a bracket 21 having two pairs of integral opposed parallel legs 22 and 23. The legs 22 are provided with registering perforations aligned with the eyelets 14 in the side walls 12 which receive the guide rod 16. The said guide rod is provided with an intermediate annular groove 24 in which is engaged one end of a bow spring 26 having forked ends, the spring being disposed between the legs 22 as illustrated in Fig. 4, thereby locking the guide rod 16 to the bracket 21, so that movement of the lever 18 will effect corresponding movement of the guide rod. The other pair of legs 23 are each provided with a slot, the slots being in registration to receive a bar member 27, one end of which is adapted to engage an end wall 13 and the other end of which is notched to engage with a forked end of a rod 28 which passes through an aperture in the opposite end wall 13.

A compression spring 29 is on the rod 28, one end of the spring bearing on the forked end of the rod 28 and the other end of the spring bearing against an end wall 13. Extension lugs 31 are formed integrally with the legs 23 of the bracket 21 and these serve to engage in slots in an insulating member 32 resting on the said legs and secured to the bracket by deformation of the legs 31. The lever 18 is provided with a boss 33 stamped near one end thereof said boss being adapted to engage the rear wall 11 so as to maintain the lever 18 in substantially parallel and spaced relation to said wall. The spring 29, in cooperation with the rod 28, acts as a means for effecting a positive drive of the lever 18, once the same has reached an over-center position. Thus, a positive action of the switch-actuating means is effected when the lever 18 is moved from one position to another.

The structure just described may be used with a variety of switch contact arrangements for actuating a combination of circuits to meet various requirements. Any one of a plurality of plates 34 each carrying differently arranged electrical terminals and switch contact blades and contact points may be mounted on the housing 10 as to be engaged by the insulating member 32 carried on the bracket 21, which member lifts or presses the blade arms carrying the contact points, depending on whether the contact points are in normally open or closed position. As is apparent, the plate 34 is formed of insulating material and is provided with a series of slots 36 along the peripheral edges which receives the lugs 37 integral with the walls of the housing, said lugs being adapted to be bent inwardly to engage in the slots and thereby secure the plate to the housing. The plate 34 is preferably formed with a plurality of apertures 38, suitably arranged, some or all of which may be used in a particular arrangement of contact points and terminals.

In the embodiment illustrated in Figs. 1—4, the plate 34 carries two spaced switch arms 39 connected to terminals 40 which extend through the apertures 38. The contact points of these arms are normally engaged with the contact points carried on the terminals 41. It will be apparent that, as the lever 18 is actuated in one direction or another, the member 32 engages with one or the other of the arms 39 to urge a respective contact out of engagement, with a corresponding stationary contact, thus opening a circuit.

With the switch arm and contact arrangement illustrated in Figs. 1—5, it is required that a neutral position be provided for the switch lever 18 and member 32 so that both sets of contacts may remain in closed condition. Accordingly, a detent 43 is struck out of the lower end 13 of the housing 10, the said detent being in registering alignment with the end of the member 27 which normally engages against the lower end wall 13 in its travel. The detent is located at the medial position of the lever travel so that, when the said lever reaches the medial position the mem-

ber 27 engages in the detent 43 as illustrated in Fig. 5 to hold the lever in such position until it is further actuated.

In the arrangement illustrated in Fig. 6, the contacts are disposed in normally open position, and accordingly as the member 32 is moved by the lever 18 from one position to another a corresponding switch arm 44 is engaged by the member 32 to urge a respective contact carried on an intermediate arm 46 into closed position with a cooperating contact carried on a fixed terminal 47 to close a circuit.

In Fig. 8, another arrangement of switch arms and contacts in normally closed disposition is illustrated. The ends of the switch arms 48, when selectively engaged by the member 32, are caused to separate respective contacts carried on the arms from cooperating stationary contacts and thereby open a circuit. It will be understood that a detent 43 is provided only in cases where it is required that the lever 18 snap into an intermediate position, as illustrated in Fig. 2. It will also be understood that the switching mechanism of my invention may be used with a variety of combinations of switch arms and contacts and that the invention is not limited only to those illustrated.

Various changes coming within the spirit of my invention may suggest themselves to those skilled in the art. Hence I do not wish to be limited to the specific embodiments described or uses mentioned, but intend the same to be merely exemplary, the scope of my invention being limited only by the appended claims.

I claim:

1. A slide type switch comprising a pair of spaced supports, a guide rod axially reciprocable in said supports, an operating lever fixed to said guide rod and extending laterally thereof, said lever being arranged for straight-line reciprocable movement, a coil spring having one end operatively connected with said lever and extending generally laterally of said guide rod and in a plane generally parallel to the plane of travel of said lever, the other end of said spring being retained at a spaced point substantially medially of the travel of said lever, a switch-actuating element associated with said lever and movable in a straight line therewith, and a relatively stationary switch element disposed in the path of travel of said actuating element and adapted to be actuated thereby, said lever being shiftable to bring the spring end operatively connected with the lever upon one side or the other of the point of retention of the opposite end of the spring, whereby the spring pressure aids in the movement of said lever to one of its alternate points.

2. A slide type switch including an operating lever arranged for straight-line reciprocable movement in a direction transverse to its longitudinal axis, an elongated coil spring having one end operatively connected with said lever and extending generally laterally of the direction of travel of said lever and parallel to the plane of travel thereof, the other end of said spring being retained at a spaced point substantially medially of the travel of said lever, a switch-actuating element associated with said lever and movable in a straight line therewith, and a relatively stationary switch element disposed in the path of travel of said actuating element and adapted to be actuated thereby, said lever being shiftable to bring the spring end operatively connected with the lever upon one side or the other of the point of retention of the opposite end of the spring, whereby the spring pressure aids in the movement of said lever to one of its alternate positions.

3. In a slide type switch, an operating member arranged for straight-line reciprocable movement, an actuating element carried by said member, a pair of spaced relatively stationary switch elements disposed in the path of travel of said actuating element and adapted to be alternately actuated thereby, spring means having one end connected to said member and extending generally laterally of the direction of travel of said member and in a plane substantially parallel to the plane of travel there-

of, the other end of said spring means being retained at a point substantially medially of the travel of said lever, said lever being shiftable to bring the movable end of the spring means upon one side or the other of the point of retention of the opposite end of said spring means, whereby the spring pressure aids in the movement of said operating member to one of its alternate positions.

4. In a slide type switch, a casing having opposed sides and end walls, each of said end walls having a longitudinal slot therein with the slots in registration and each of said side walls having an aperture therein with said apertures being in registration, a guide rod axially reciprocable in said apertures, a lever extending through said slots transversely of said guide rod, a bracket member fixed on said lever, means securing said bracket member to said guide rod, whereby said lever and said guide rod move simultaneously, a member slidably supported in said bracket in parallelism with said lever and having one end in engagement with one of said end walls, a rod member hingedly connected to the other end of said slidable member, the other of said end walls having an aperture substantially medially thereof, the other end of said rod member being loosely received in said aperture in said other end wall, a coil spring carried coaxially of the said rod and normally urging said slidable member into engagement with a respective end wall, said last mentioned end wall having a detent medially thereof engageable by said slidable member to arrest movement of said lever at a medial point, said lever being shiftable to bring the spring end adjacent said slidable member upon one side or the other of said medial detent, whereby the spring pressure aids in the movement of said lever to one of its alternate positions.

5. In a slide type switch, a casing having opposed side and end walls, each of said end walls having a longitudinal slot therein with the slots in registration and each of said side walls having an aperture therein with said apertures being in registration, a guide rod axially reciprocable in said apertures, a lever extending through said slots transversely of said guide rod, a bracket member fixed on said lever, means securing said bracket member to said guide rod, whereby said lever and said guide rod move simultaneously, a member slidably supported in said bracket in parallelism with said lever and having one end in engagement with one of said end walls, a rod member hingedly connected to the other end of said slidable member, the other of said end walls having an aperture substantially medially thereof, the other end of said rod member being loosely received in said aperture in said other end wall, a coil spring carried coaxially of the said rod and normally urging said slidable member into engagement with a respective end wall, said last mentioned end wall having a detent medially thereof engageable by said slidable member to arrest movement of said lever at a medial point, said lever being shiftable to bring the spring end adjacent said slidable member upon one side or the other of said medial detent, whereby the spring pressure aids in the movement of said lever to one of its alternate positions, an actuating element carried on said bracket member, and a pair of spaced relatively stationary switch elements disposed in the path of travel of said actuating element and adapted to be alternately actuated thereby.

6. In a slide type switch, an operating member arranged for straight-line reciprocable movement, a wall portion disposed in parallel relation to the plane of movement of said member, a slidable member carried on said operating member and having one end engageable with said wall portion, said wall portion having a detent medially thereof adapted to be engaged by said slidable member to arrest movement of said operating member at a medial point in its travel, a coil spring having one end engageable with the opposite end of said slidable member, the

other end of said spring being retained relatively stationary at a spaced point in substantial alignment with said detent, said spring normally urging said slidable member into engagement with said wall portion, a switch-actuating element carried on said operating member, a relatively stationary switch element disposed in the path of travel of said actuating element and adapted to be actuated thereby, said operating member being shiftable to bring the spring end engageable with the slide member upon one side or the other of said detent, whereby the 10 spring pressure aids in the movement of said operating member to one of its alternate positions.
